United States Patent

Des. 235,446
Patented June 17, 1975

235,446

BATHTUB

Stanley F. Korol, Mansfield, Ohio, assignor to Borg-Warner Corporation, Chicago, Ill.

Filed Aug. 20, 1973, Ser. No. 389,904

Term of patent 14 years

Int. Cl. D23—02

U.S. Cl. D23—55

Fig. 1

Fig. 2

Fig. 3

Fig. 4

FIG. 1 is a perspective view of a bathtub showing my new design;

FIG. 2 is a top plan view thereof;

FIG. 3 is a cross sectional view taken on line 3—3 of FIG. 2; and

FIG. 4 is a cross sectional view taken on line 4—4 of FIG. 2.

I claim:

The ornamental design for a bathtub, as shown.
